PEN AND PENCIL HOLDER

Joseph I. Crea, St. Paul, Minn.

Application October 22, 1953, Serial No. 27,276

Term of patent 14 years

(Cl. D74—21)

Fig. 1

Fig. 2

Fig. 3

To all whom it may concern:

Be it known that I, Joseph I. Crea, a citizen of the United States, residing at St. Paul, county of Ramsey, and State of Minnesota, have invented a new, original, and ornamental Design for a Pen and Pencil Holder, of which the following is a specification, reference being had to the accompanying drawing, forming a part hereof.

I claim:

The ornamental design for a pen and pencil holder, as shown.
